ABSTRACT: A linear-to-pivotal motion converting mechanism including a pair of blades pivotally secured at the ends in spaced relation in the form of a variable-area quadrilateral, hubs mounting the blades for pivotal movement about points displaced from the centers of the respective blades and an actuator for moving the hubs apart transversely thereby causing the blades to pivot about the hubs is disclosed. An electrical switch utilizing the mechanical movement is also disclosed. The switch is suitable for miniaturization as a microswitch and provides a knife switch wiping action with electrical contacts.

KNIFE BLADE MICROSWITCH

This invention relates to electrical switches in general and more specifically to miniature electrical switches commonly referred to as microswitches. More specifically, this invention relates to a microswitch using a novel linear-to-pivotal motion converting mechanism in which electrical contact is completed by knife switch wiping action.

Microswitches of several designs are commonly used throughout industry. Most of these microswitches which are standard in the industry suffer from several deficiencies. For example, such switches often fail to maintain open and/or closed contacts due to the inherent susceptibility of commonly used reed-type contacts to shock or vibration. Motion suddenly imparted to the switch housing causes the reed to flutter in the housing thereby making or breaking electrical contact independent of any actuation. This sensitivity of the microswitch to vibration results from an unbalanced or asymmetrical configuration with respect to the pivot points of the movable elements, the reed for example, in the switch. This difficulty is overcome in the present invention in which one feature is the arrangement of the masses of the linkage elements in perfect balance about any and all axes through the rotational center of the mechanism. Acceleration forces due to shock, vibration or change of velocity, therefore, cannot exert a force to cause motion in the switch mechanism or the electrical contacts. An important feature of the invention, then, is a microswitch design which is substantially unaffected by external acceleration.

In addition to being sensitive to shock or vibration, contemporary microswitches are frequently subject to failure due to contamination on the contact points. These contact points are quite small, particularly on the subminiature switches, and the point contact pressure is low. Microscopic particles of non-conductive material, such as lint, settling between the points effectively prevent electrical contact and can be responsible for serious failures of entire systems. Such contamination is particularly hazardous where the switch is used in a vibrating environment which can mobilize foreign particles within the switch housing.

When microswitches are used in a cryogenic environment, icing of the contact points is a rather common failure. Electrically conductive wire, such as copper, is an excellent conductor of heat and the switch contacts are likely to be the coldest elements in the switch housing. Consequently, any moisture in the gas in the housing will condense on the contacts to form a thin layer of ice. Electrical contact is not entirely prevented, but since the ice is a very poor electrical conductor, icing of the contacts may result in serious failures.

The foregoing difficulties are overcome in the present invention, one feature of which is the utilization of the wiping action of a knife blade type switch. The surface area of the switch contacts, in the present invention, is several times as great as in ordinary microswitch contact points. This reduces contact resistance and increases contact reliability. The contact wiping action is self-cleaning, as opposed to the ordinary microswitch "kissing" contact. Indeed, the knife blade switch has been recognized as one of the most reliable of all electrical mechanisms.

The foregoing difficulties are also obviated to a large degree by the present invention in which one feature is the provision of an actuating mechanism which permits encapsulation of the entire switch. Actuation may be accomplished through an air-tight bellows, for example. This allows evacuation of the switch and, if desired, backfilling with dry gas or an inert gas, such as helium for cryogenic applications. This also prevents entry of foreign particles into the switch housing. Switches so encapsulated and actuated are, of course, suitable for use in virtually any environment, such as under water, in chemical operation, etc.

Microswitches generally lack sufficient overtravel of the switch-actuating plunger. This makes proper adjustment of mechanical actuating means very difficult and is often impossible to accommodate for dimensional variations caused by changes in temperature or by changes in load deflection. Buil-

dup of foreign substances on the actuator member is also a frequent problem. These problems are usually solved by interposing a spring deflection device as a safeguard between the switch and the switch actuator. In certain instances, the space occupied by such spring deflection devices and the weight contribution of such devices may pose problems in addition to those previously noted. One of the features and advantages of the present switch design is that overtravel two or more orders of magnitude greater than is possible with contemporary microswitches is easily provided. Any required degree of overtravel is simply achieved without significant modification of the overall design. Pretravel, in addition, may be virtually eliminated or any desired level of pretravel provided.

Conventional contemporary microswitches are available off the shelf in the single pole, double throw configuration. This switch can, of course, be used as a single pole, single throw switch but when double throw, or triple or quadruple pole switches are required, as is frequently the case, it is necessary to connect two or more switches together side to side and to actuate them with a special actuator. Aside from the increased weight and bulk, which may present problems in certain environments, simultaneous actuation is not always achieved. These disadvantages are overcome by one feature of this invention in which a microswitch can be easily and economically produced as a standard component which is suitable for use as a single, double, triple, or quadruple pole, single or double throw switch.

By combining the several advantageous features of this invention, a simple, reliable, microswitch which is immune to shock or vibrational forces, and which employs an efficient knife blade contact wiping action with large overtravel capability and with multiple-circuit provision is available. The switch is readily adaptable to being hermetically sealed and, with state of the art adaptations, can be easily converted to a pressure-sensing, temperature-sensing, or other environmental characteristic sensing switch or to a switching relay.

Another feature of the invention is that the switch can be manufactured from readily available, inexpensive materials to easily obtainable tolerances and without the necessity for threaded holes, screws, etc. The simplicity of the mechanism and assembly will, therefore, permit low unit production costs with minimum tooling costs. The disadvantages of close tolerance requirements and special alloy and material requirements often encountered in the manufacture of microswitches of the prior art are thereby avoided.

The advantages of this invention are obtained through the use of a novel mechanical movement which, in itself, constitutes one of the important features of the invention. This movement comprises a pair of elongate members which are pivotally secured near the ends thereof in relatively spaced relation, so as to form a quadrilateral which is variable in area and in width, (the width being measured perpendicularly from the respective members). The elongate members, in the form of rods, blades, etc., are substantially rigid and are individually mounted for pivotal movement about respective pivot points and reciprocal movement transversely of the longitudinal axes of the members. One or both pivot points are displaced from the centers of the respective members. Preferably, the pivot points of both members are displaced from the center, but are asymmetrically located. Actuating means are provided for reciprocally moving the mounting means apart or together, transversely with respect to the members, the coaction of the end interconnection, pivotal mounting and relative transverse motion causing the members, referred to for convenience as blades, to pivot about the mounting means. A variety of actuating means may be provided.

The switch of this invention includes the aforesaid mechanical movement in a switch housing which also comprises one or more electrical contact sets positioned so as to be opened and/or closed by the reversible pivotal movement of the blades when actuated or deactuated. An important feature of the invention is the provision of a plurality of electrical contacts in the switch actuatable by the same pivotal movement of the blades.

Other novel and important features and advantages of the invention will become apparent from the specification which follows and from the drawings to which reference is now made.

FIG. 1 is a perspective view of one embodiment of the switch of this invention, showing a bellows actuator and being suitable for hermetic sealing.

FIG. 2 is a cross-sectional view of a variation of the switch of FIG. 1 corresponding to a view taken substantially along lines 2-2 looking downwardly in the direction of the arrows as shown in FIG. 1, showing the mechanical movement of the switch in a first, deactuated, position.

FIG. 3 is a cross-sectional view corresponding to a view taken substantially along lines 3-3 of FIG. 1 looking sideways in the direction of the arrows, showing one embodiment of the mechanical mechanism and the switch in the first, deactuated position, as in FIG. 2.

FIG. 4 is a cross-sectional view corresponding to a view taken substantially along lines 2-2 of FIG. 1 looking downwardly in the direction of the arrows, as in FIG. 2, but showing the mechanical movement and switch of this invention in the second, actuated, position.

FIG. 5 is a side cross-sectional view corresponding to a view taken substantially along lines 3-3, as shown in FIG. 1, showing the mechanical movement and switch of this invention in the second, actuated, position as in FIG. 4.

FIGS. 6 and 7 are schematic representations showing alternative actuating mechanisms.

FIGS. 8, 9 and 10 illustrate another embodiment of the invention in miniature form; FIG. 8 being a side view of the switch shown in cross section; FIG. 9 being a cross-sectional view taken along lines 9-9 of FIG. 8, and FIG. 10 being a partial cross-sectional view showing the switch operating structure taken along lines 10-10 of FIG. 8.

The mechanical construction and operation of the movement and switch of this invention will be explained for purposes of reference hereinafter. It is to be understood that the embodiments of the invention described and illustrated exemplify the mechanical movement and an application of the mechanical movement to a particular switch geometry, and that the illustrations are not limitive of the scope of the invention.

The switch 10 of this invention, as illustrated in FIG. 1, includes a housing which, as will be explained in greater detail hereinafter, is suitable for being hermetically sealed.

As best illustrated in FIGS. 2 and 3, the housing, in the embodiment illustrated, comprises a top plate 12, a bottom plate 14, and spacer sections 16, 18, 20 and 22 forming the sidewalls of the housing. The embodiment is an illustration of a working model of the invention wherein the spacers and top and bottom plates of the housing were separate elements. It is contemplated, however, that in production the housing will be made of two units adapted to be joined to form a closed housing. In the illustration the housing is substantially square but, as will be explained hereinafter, the housing may advantageously be rectangular rather than square, or may be in a variety of configurations. As in electrical switches generally, the housing is preferably made of an insulating material such as a phenolic resin, nylon, ceramic material, etc. The switch of this invention may, of course, be constructed according to the design criteria discussed herein using conventional mechanical and electrical engineering principles in the production of the switch and in the adaptation of the switch to particular uses.

In the illustrated embodiment of the invention one of the spacers, 22, is provided with an aperture, shown at 24, and a grommet 26 through which a multiconductor cable 28 extends.

The individual conductors 30 and 32 for example, are connected to the electrical contacts in the housing as illustrated, for example, at 34 and 36, forming one set of contacts, and at 38 and 40 forming a second set of contacts. Additional pairs of contacts shown at 42 and 44 and at 46 and 48 are also conveniently provided. One, two, three or four sets of contacts are

easily provided as shown in the illustration. Each set of contacts may include a single contact or two, three or more contacts depending upon the switching requirements. When the switch of this invention is miniaturized to form a microswitch, the number of contacts would be limited by the space available in the housing, but eight or 12 contacts are easily provided.

The contacts are in the form of leaf springs and are conveniently carried on the supports 50, 52, 54 and 56 as illustrated in FIGS. 2 and 3. These supports may be made of any conventional insulating material and are conveniently formed integrally with the housing. The contacts may be secured to the supports and the conductors 30 and 32, for example, to the contacts by screws, as illustrated, or preferably by soldering, riveting, or the use of simplified frictional fasteners. When the switch is miniaturized, contact connections can easily be made using printed-circuit techniques.

Electrical contact is completed and broken by the reversible pivotal movement of the mechanism of this invention, the operating elements of which comprise members 58 and 60, which are referred to as blades in the switch of the invention. While several alternative modes of construction and electrical circuit making and breaking are possible, in a preferred embodiment of the invention the blades 58 and 60 are composed, in part at least, of an insulating material such as phenolic resin or phenolic resin bonded glass or other fabric, ceramic material, or any other insulating material of suitable strength.

The blades 58 and 60 carry one or more conductive leaves, such as the leaf 62 which is illustrated in FIG. 2 as completing a circuit between contacts 34 and 36. The conductive leaf 64 is adapted to resiliently displace one or more contacts, 38 and 40 for example, by wiping action to complete the circuit therebetween. The leaf 66 is adapted to make the electrical circuit between the contacts 42 and 44 and the conductive leaf 68 is adapted to complete the circuit between the contacts 46 and 48 in the same manner, as shown in FIGS. 2-5.

The conductive leaves, in this embodiment of the invention, are bonded by adhesive, friction fit or otherwise to the blades 58 and 60, respectively, and they are composed of a conductive material. According to good electrical engineering practice the conductive material may be silver, copper, silver-plated copper, brass, or other conductive material. In certain instances it may be desirable to use a hard metal as the leaf, such as tungsten or tungsten alloys, where contact resistance is less important than wear resistance.

One or more of the conductive leaves may be electrically interconnected by any desired circuitry. Printed circuit techniques are preferred in the microswitch embodiment of the invention. Electrical interconnection between leaves on the respective switch blades may be accomplished through the use of flexible conductors, springs, or through the interconnection between the switch blades. The number of conductive leaves, the configuration and placement of the conductive leaves, and the interconnection therebetween, is subject to great variability depending upon the switching requirements. The embodiment illustrated is suitable for producing the switches on a mass production scale for general use. For particular applicability, custom design of the switching arrangement and interconnecting circuitry may be easily accomplished. The number and configuration of contacts, leaves, etc. and interconnection is limited only by the space available in the particular housing. Thus, extreme miniaturization may limit the number of contacts to eight, as shown in the illustration, while custom switching of a large number of circuits may be accomplished using larger switching components.

Similarly, the current capacity of the circuit switched is limited by the size of the contacting surfaces; thus the switching of extremely heavy electrical currents will require larger switching components. All these considerations are, of course, well within the skill of the art.

In the illustrated embodiment, the switching is accomplished by conductors carried on the switch blades. It will be understood, however, that the switch blades may indirectly actuate switching. That is to say that the mechanical motion

available through the movement of this invention may be used as an actuating motion for making and breaking electrical switches which are electrically independent of the switch blades. The movement of this invention, then, may be used merely to impart actuating motion to an otherwise separate switching system. Indeed, the mechanical movement of this invention has utility completely distinct from the switching application in which it is embodied in the illustrations of FIGS. 1-5.

The blades 58 and 60 are pivotally secured proximate the ends thereof in relatively spaced relation, as illustrated. The blades may be secured proximate the ends thereof by a pair of end connectors 70 and 72 which are respectively pivotally connected near the ends of the blade as, for example, by the pins 74 and 76 and the pins 78 and 80. The blades and the end connectors define a quadrilateral which is variable in area and in width, as the width is measured perpendicularly from the respective blades. Thus, the area of the quadrilateral and the perpendicular width between the blades is greater in the actuated position than in the deactuated position. This is illustrated by comparison of FIG. 2 which shows the switch in the deactuated position, and FIG. 4, which shows the switch in the actuated position. The area in the first position, shown in FIG. 2, is less than the area of the quadrilateral in the second position, as shown in FIG. 4.

Means are provided for mounting the blades individually for pivotal movement about a point intermediate the end of each blade, at least one of the points being displaced from the respective centers of the blades. Stated differently, the pivot points for the blades must not both lie on a line bisecting the blade axes perpendicularly. One of the points may lie on the perpendicular intersecting line but if both points lie on the perpendicular bisecting line, then the switch is inoperative.

Both of the pivot points may lie on one side of the center of the respective blades to provide an operative switch and mechanical movement. This, in certain instances, may be highly desirable. In providing a vibration- and shock-resistant switch, however, if it is desirable to provide a symmetrical arrangement in which the masses of the linkage elements are always balanced about any or all axes through the rotational center of the mechanism. Thus, in the preferred embodiment, the mounting means for the respective blades are so arranged that the blades pivot about respective points which are equally displaced on opposite sides of the center of the respective blades. This is the embodiment illustrated in FIGS. 2-5.

Referring to FIGS. 2 and 3 in particular, with comparative reference to FIGS. 4 and 5, the mounting means for the blades comprises a pair of hubs indicated at 82 and 84 in FIG. 2. The hub 82 is illustrated in elevation in FIG. 3 and comprises a generally cylindrical body portion shown at 86, and enlarged generally cylindrical body portion shown at 88 and a chamfered interconnecting portion 90 between the portions 86 and 88 providing a frustoconical camming surface. The hub 82 also includes upper and lower annular grooves shown at 92 and 94 and is mounted for rotation in a pair of slots 96 and 98 by means of the pins 100 and 102. The slots 96 and 98 are oriented so as to extend transversely of the blade axes to permit transverse movement of the hubs upon actuation and deactuation, as will be explained in detail. Oversize holes may be substituted for the slots to permit transverse movement of the hubs, but more precise action is obtainable using elongate slots having a width approximately equal to the diameter of the pins 100 and 102. The blade 58 may be formed integrally with the hub 82 or it may be secured thereto by a weld such as shown at 104, or any other convenient means.

The hub 84 is of like construction comprising a cylindrical portion 106, an enlarged cylindrical portion 108 joined by a chamfered portion 110 forming a frustoconical camming surface and including a pair of grooves 112 and 114. The hub 84 is secured in the housing by means of the slots 116 and 118 and the pins 120 and 122 in the manner described with respect to the other hub 82.

The hubs 82 and 84 are resiliently biased toward each other by a constraining ring 124 at the top, best illustrated in FIG. 2, and by a similar constraining ring 126, at the bottom illustrated in FIG. 3. Upon actuation, the constraining ring 124 is resiliently deformed, as shown by a comparison of FIGS. 2 and 4. Upon deactuation, the hubs are returned to their first, deactuated, position by the resilient force exerted by the constraining rings 124 and 126. Equivalently, the hubs may be biased outwardly apart and the actuation may be accomplished by means for moving the hubs together against the bias force.

The switch is operated by moving the separator means in the form of an actuator cam 128 downwardly from the position shown in FIG. 3, the first, deactuated, position to the position shown in FIG. 5, the second, actuated, position. The actuator cam includes a cam-operating surface which is complementary with the camming surfaces 90 and 110 of the hubs 82 and 84 and causes the hubs 82 and 84 to move apart. The actuator cam 128 is secured to a motion-transmitting means such as a cylinder 130 which fits over a guide pin 132 and is free to slide in reciprocal motion through a collar 134. External actuation of the switch is accomplished by pushing the button 136, which is resiliently biased by a spring 138 in the upward position, which corresponds to the first or deactuated position. A stop 140 may, if desired, be provided in the cylinder 130 to limit the movement of the operator button 136.

The switch of this invention is conveniently arranged for being hermetically sealed. In this configuration, the operator button 136 is modified to include a bellows, as shown at 142 in FIG. 1, which is secured to the housing. Actuation is accomplished by compressing the bellows. In this manner, by sealing the cable entry into the housing, the entire switch can be evacuated and, if desired, backfilled with a dry gas, an inert gas such as nitrogen or, for cryogenic operation, helium to prevent condensation. Once sealed, the switch is completely unaffected by its environment.

There are a number of alternative mechanisms by which the mechanical movement of this invention, and the switch, can be actuated. For example, FIG. 6 shows an alternative embodiment of the actuating mechanism of the invention in which the blades are carried by a pair of hubs 144 and 146 and are constrained toward each other in contact or substantial contact with an idler hub 148 by means of a plurality of constraining devices, such as the ring 150. Actuation is accomplished by separator means in the form of a rod 152. In FIG. 6, the mechanism is shown in the deactuated position. Upon actuation, the rod 152 is moved inwardly between the hub 146 and the idler hub 148. This causes the hub 146, which is mounted by means of a pin 154 in slot 156, to move outwardly, to the left as shown in FIG. 6, and likewise causes the idler hub 148, which is mounted by means of pin 162 in slot 164, and the blade-carrying hub 144, which is mounted by means of pin 158 in slot 160, to move outwardly, to the right in FIG. 6. This causes equal separation of the hubs in the respective directions and consequent actuation of the mechanism and the switch.

In FIG. 7, the idler hub is dispensed with. The blade-carrying hubs 166 and 168, which may be mounted as previously described, are constrained resiliently together by the ring 170 and are actuated by insertion of the rod 172 which, in a preferred embodiment, has operating surfaces 174 and 176 conforming to the surfaces of the hubs. As the rod 172 is forced between the hubs 166 and 168, these hubs are moved apart thereby actuating the mechanism according to the principles to be described. Actuating means of any type suitable for moving the mounting means and blade pivot points transversely for causing the blades to pivot about the mounting means may be provided equivalently. The actuating mechanism shown in FIGS. 2 through 5 is preferred, however.

The operation of the mechanical movement, and the switch, of this invention is best understood by comparison of FIG. 2 with FIG. 4 and FIG. 3 with FIG. 5. The conversion of the linear movement of the actuating means, the cam 128 for ex-

ample, to partial rotary, or pivotal, movement may be explained by considering the blades 58 and 60 respectively, as first-order levers, with the pivot point at one end and the load at the other end. It will readily be seen that both ends are pivot points and loads, however, and that the direction of pivotal movement will depend upon the relative load applied at the respective ends of the lever.

Consider first the case wherein the separating force is exerted in the exact center of the levers in directions perpendicular to the lever axes. In this case, the load will be applied equally at both ends of each lever. Since the forces are balanced, no pivotal motion will occur and the mechanism is inoperative.

Now consider the case wherein the point of application of force is displaced proportionally an equal distance toward the same end of the respective levers from the center, for example one-quarter the distance from the center to the same end of the respective levers. While the force is applied unequally to the opposite ends of an individual lever, an equal and oppositely directed force is exerted on the same end of the respective levers by virtue of the end connector therebetween. Since the forces are equally balanced at the ends, no pivotal movement will occur and the mechanism is inoperative in this configuration.

Thus, when the point of application of force is symmetrical, i.e., directed perpendicularly to the lever axis at proportionally corresponding points on the respective levers, the device is inoperative. In the preferred embodiment, the levers and end connectors form a quadrilateral which is symmetrical, i.e., a parallelogram, but the same principles will apply even though the levers and end connectors are asymmetrical forming a trapezoid.

Consider now the case wherein the force is applied asymmetrically. That is, where intermediate pivot points are located and the force is applied at points on opposite sides of the lever centers or unequally spaced on the same side of the lever centers, or in differing directions upon the respective levers, relative to the respective lever axes. In any of these situations, the forces at the ends of the levers will not be balanced and the levers will pivot until the vectoral forces at the ends come into balance, or the pivotal movement is constrained by an external force such as electrical contacts.

Vibration and shock from impact of the blades, during pivotal movement, with contacts is easily prevented by positioning the contacts for being opened and closed by the reversible pivotal movement of the blades and such that the blades come to rest, as a result of the balance of vectoral forces at the ends thereof, when the respective contacts are actuated. In the preferred embodiment, the contacts, or other stop mechanisms, are positioned so as to stop the pivotal movement of the blades just slightly short of the vectoral balance point, thus placing the contacts and the mechanism of the movement under slight but controlled tension during actuation. Following the principles outlined herein, this is easily accomplished using conventional principles of mechanical engineering.

The area of the parallelogram defined by the pivot members, blades 58 and 60, and the connecting rods 70 and 72 increases upon actuation through a maximum, when the parallelogram is a rectangle, and then decreases. The switch is preferably designed such that the area in the deactuated position is smaller than the area in the actuated position, although this is not necessary to the operability of the switch.

It will be apparent from the foregoing that the blades cannot be considered as true first-degree levers since, first, the blades are pivoted at both ends, rather than at only one end. Secondly, the point of application of force also constitutes the main pivot point of the lever. The mechanical movement, therefore, constitutes an application of the principles of both the first-order lever and the third-order lever. The movement can also be analogized to other fundamental mechanical movements but it is believed that the foregoing analogy is sufficient for an understanding of the movement and the switch of this invention.

In order to provide a balancing of masses of the movement about the pivotal axes, providing mechanical stability, ease of operation, minimum friction, and insensitivity to shock and vibration, it is desirable to provide pivot points on opposite sides of the centers of the respective levers. The pivot points are preferably displaced an equal distance on the opposite sides of the blade centers. The blades, as measured between the end pivot points, are preferably of equal length and the end connectors are also of equal length, when similarly measured.

The degree of rotation obtainable, about the pivot point of the respective blades, is a function of the relative length of the blades, the length of the end connectors, and the amount of reciprocal movement of the pivot points of the blades. For convenience, the relative dimensions and distances may be considered in terms of the length L , which is the length of the respective blades as measured from the center pivot point thereof to the end pivot point thereof which is closest to the center pivot point, i.e., L is the short leg of the blade. $L + \Delta L$ is the long leg of the blade, or the distance from the center pivot to the end pivot furthest from the center pivot point. The length of the end connectors may be identified as l . The minimum distance between the pivot points of the respective blades is referred to as D and the maximum distance between the center pivot points of the respective blades is referred to as $D + \Delta D$, ΔD constituting the distance increase between the intermediate pivot points upon actuation of the mechanism.

A convenient and easily operated movement and switch can be constructed by designing the movement such that the distance ΔL , which is the difference in length between the long leg and the short leg of the blade, is equal to the total movement distance between the two intermediate pivot points ΔD .

In a specific embodiment, ΔD and ΔL are designed to be 0.018 inch. In obtaining this ΔD , the hubs and the actuator cam are chamfered on a two-to-one slope, 0.018 inch longitudinally by 0.009 inch radially, giving a total displacement of 0.018 inch. L was designed to be 0.216 inch and the end connector length, l , was designed to be 0.125 inch.

A switch constructed on these ratios provides approximately 60° total rotation from the deactuated position, illustrated in FIG. 2, to the actuated position, illustrated in FIG. 4. Coincidentally, the torque available to overcome the system friction, in inch-pounds per pound of load, separating the pivot points is numerically approximately equal to ΔL . Thus, for a ΔL of 0.018 inch, the required torque is 0.018 inch-pounds per pound of separating force and a ΔD of 0.018 inch provides 60° of linkage rotation.

One of the important features and advantages of the invention results from the use of an actuating means of the type illustrated in FIGS. 2 through 5, or one of the equivalent actuating means, since the friction in the linkage is virtually eliminated or very substantially reduced. The rotation of the hubs 82 and 84, for example, induces rotation of the center roller actuating cam 128. This effectively reduces friction since the contacting surfaces roll approximately six-sevenths of their travel while sliding about one-seventh. Further depression of the actuating cam, past the 0.018-inch travel, does not affect the linkage position and, therefore, affects any desired overtravel. Upon release of the load on the actuator button, the actuator button is returned to its initial position by the spring 138 and the hubs are returned to their initial position, pivoting the blades in the reverse direction, by the restraining bias means, the resilient rings 124 and 126.

Instantaneous make and break of the contacts is easily obtainable simply by providing an actuating cam with cam-operating surfaces on the top and bottom. Thus, when the actuating cam is pushed through the permitted travel, the hubs are first displaced outwardly, as explained, and then permitted to return as the double chamfered actuating cam continues movement. The reverse process is obtained when the actuating cam is moved in the opposite direction. Thus, a signal of any desired predetermined duration can be achieved by controlling the rate of movement and the length of the actuating cam.

Another embodiment of this switch is illustrated in FIGS. 8, 9, and 10, to which reference is now made. In this embodiment, the switch is enclosed in a housing 200 having a top 202, a bottom 204, ends 206 and 208 and sides 210 and 212. The case, as illustrated, may desirably be made of two side sections which have apertures 214 and 216 on one side and apertures 218 and 220 on the other side so as to be in register. The sides are held together by hollow shafts 222 and 224 and/or by adhesive as required or by any other suitable means. The case forms an aperture 226 and may include insulating plates 228 and 230 at the ends, 232 on the bottom, and 234 and 236 on the respective sides.

A pair of hubs 238 and 240 are received on the shafts 222 and 224 loosely so as to permit relative rotary and lateral movement. A pair of pivot levers 242 and 244 are received on hub 238 and similar pair of pivot levers 246 and 248 are received on hub 240. The hubs are held in spaced relation on the respective hubs and pivotally interconnected by a bottom connecting rod 250 and a top connecting rod assembly shown generally at 252.

The bottom connecting rod 250 may comprise a single elongate flat element bored at the respective ends for receiving a pivotal connecting pin, and forming a large elongate open space in the central area to accommodate the actuating mechanism, as will be described later.

The connecting rod 250 interconnects the lower ends of the respective sets of pivot levers by means of pivot pins 254 and 256. The form of the connecting rod, obviously, is of little consequence in this embodiment of the invention since it is not utilized for switching. By a slight modification thereof, however, according to the principles and design criteria applied to the top connecting rod, to be described, the bottom connecting rod may be used for switching as well.

The top connecting rod assembly 252 comprises a pair of elongate parallel rods 258 and 260 which are bored at the respective ends for receiving the pivot pin connectors 262 and 264. These elongate parallel connecting rods, which form part of the connecting rod assembly 252, are held in spaced relation by a pair of insulating gaskets 266 and 268, an insulated spacer 270 and a conductive sleeve 272 at one end, best shown in FIG. 10, and a similar construction at the other end comprising an insulating spacer 274 and a conductive sleeve 276, shown in FIG. 8.

This combination of pivot levers and connecting rods is resiliently constrained to a first deactuated position, shown in solid line, by means of a clip spring 278 which includes curved ends 280 and 282 partially surrounding the hubs 238 and 240 and forming an aperture 284 in an enlarged central portion 286 to accommodate the actuating mechanism to be described.

The pivot mechanism is actuated by a cam 290 which includes arcuately chamfered edges 292 and 294, best shown in phantom line in FIG. 8. The cam 290 is actuated by means of a rod 296 which extends in reciprocal slideable relation through a sleeve 298 and a grommet 300 in aperture 226 externally of the housing for actuation. The rod 296 may, of course, be encased in a bellows if a gastight seal is desired. On the lower end, the cam 290 is secured to a guide pin 302 which is slideably received in a guide sleeve 304. The cam 290 is biased upwardly, as shown in FIG. 8, by a compression spring 306 received around the guide sleeve 304 and the guide pin 302 in an annular groove 306 in the bottom of the cam 290. The compression spring 306 in combination with the restraining leaf spring 278 resiliently bias the mechanism to a first deactuated position shown in solid line. Upon actuation, the cam moves downwardly causing the hubs to move apart and the lever to pivot to the actuated position, as shown in phantom line in FIG. 1.

The switch is provided with two sets of resilient spring leaf contacts 310 and 312 on one side and 314 and 316 on the other side. The contact 310 is secured to a connector 318 and the contact 314 is secured to a connector 320. These connectors extend through the housing to permit external connection to the circuit to be actuated. The contacts 312 and 316 may be

commonly connected or separately connected, as desired, in like manner, these connections not being illustrated. The connecting rod assembly and contact arrangement can be approximately duplicated on the bottom of the mechanism if desired to increase the number of switching functions possible upon actuation.

In the deactuated position, shown in solid line in FIG. 8, an electrical circuit is completed between contacts 314 and 316 by means of the conductive sleeve 272. Upon actuation, the mechanism pivots to the position shown in phantom line in FIG. 8 and the electrical circuit is completed between contacts 310 and 312 by means of the conductive sleeve 276. Electrical integrity is maintained in the switch by means of insulating mounting blocks, as required, illustrated, for example, at 322 and 324 and at 326 and 328.

It will be apparent from the foregoing that the two embodiments of the switch illustrated, while different in certain design characteristics, embody the same operating principles and fundamental mechanisms. Each of the switches comprises a pair of pivot levers which may be in the form of blades, levers, rods, etc. pivotally secured together by connecting rods. These blades or levers are mounted individually intermediate the ends thereof for pivotal movement about fixed pivot points for being respectively displaced asymmetrically from the respective centers for the blades. Actuating means for reciprocally moving the mounting means transversely of the blades or members for thereby causing the blades to pivot about said mounting means are provided. Electrical contact means are positioned for opening and closing upon the reversible pivotal movement of the blades by the actuating means, which may be a cam movably mounted for causing relative lateral movement between the hubs which mount the members for pivotal and lateral movement. These contacts may be solid fixed conductive materials but are preferably in the form of leaf springs of any desired configuration. The circuit is completed by a conductive element which may be a leaf, sleeve, etc. carried on or operated by the pivot mechanism.

The embodiments shown in the drawings are intended only to illustrate various ways in which the switch can be constructed and not as a limitation upon the possible modes of construction. Indeed, a great many variations in the actual mode of construction of the individual elements and the combination as a whole are possible using design principles well known in the art within the scope of this invention and based on the teachings herein.

It will be readily apparent from the foregoing that the movement of this invention has utility in numerous applications in addition to its use in the switch of the invention. For example, the movement is readily adaptable to form a shutter mechanism, simply by positioning the blades adjacent an aperture. Furthermore, any desired amount of amplification of linear motion into rotary motion can be achieved by providing appropriate ratios of L , $L+\Delta L$, I , D and $D+\Delta D$. Mechanical advantage is also controllable by the relative positions of the intermediate pivot points on the blades, either on the same side of the blade centers or on opposite sides thereof. In general, the greater the ratio of the distance ΔD to the length differential ΔL , the greater is the movement amplification. With an 1:1 ratio of ΔD and ΔL , an increase in ΔD results in a greater angular rotation upon actuation.

The materials of construction of the hubs and actuating mechanisms are of no particular importance; however, self-lubricating materials have certain advantages. The hubs may be made of either a conductive or nonconductive material, and likewise, the actuating mechanism may be made of either conductive or nonconductive material, regardless of the material of which the hubs are constructed. Nylon, phenolics, polytetrafluoroethylene (Teflon) of the nonconductive materials and brass, steel, aluminum and magnesium of the conductive materials are suitable. Most other hard metals and nonmetals are also suitable for use in this application. An external lubricant may or may not be provided for the mechanism, depending upon the environment in which the

mechanism operates and the materials of which the elements of the mechanism are constructed. The selection of materials is well within the skill of the art.

The design of contemporary microswitches is such that they are ordinarily actuated with an extremely light force. While this is an important requirement in some applications, it is very undesirable in a host of others. More often than not, a required activation force of a pound or two is of no consequence, since tens, hundreds and frequently thousands of pounds are available at the switch actuator. In these applications, problems of vibration and shock are frequently encountered. Microswitches designed according to the principles set forth herein are more adaptable for operation in such environments and can be constructed in essentially any configuration so as to be readily interchangeable with conventional microswitches.

Switches designed according to this invention are readily adaptable to pressure sensing, temperature sensing, or for use in switching relays, wherein the activation force is provided by an electromagnetically impelled armature.

The inventive switch was developed particularly with the object of solving difficult problems experienced in aircraft and space vehicles. In these environments, absolute reliability is critical and multiple-functioning switching circuits are frequently crucial.

A great many features of the switch can be enumerated which provide advantages over existing microswitches. These include the wiping action of contact surfaces for improving electrical conductivity, thereby reducing resistance loss, noise, and localized heating in the switch. This switch design permits a relatively wide separation of open contact surfaces. This feature plus the mass balancing of the movement mechanism inhibits and essentially prevents accidental make or break due to shock and vibration.

Any degree of overtravel desired for a particular environment can be provided. Any degree of pretravel can easily be provided and, if desired, pretravel can be virtually eliminated according to the design principles set forth. Friction in the mechanism is reduced to a negligible quantity by virtue of the design geometry which employs rolling action at 10 important friction points. This leaves most of the operating torque available for doing useful work in making and breaking the contacts.

Loading on the operating mechanism is restricted to that force which is imposed by the ring return springs, 124 and 126, or such equivalent biasing mechanism as is selected. Coil springs, with suitable interconnection, for example, can be adjusted to give any desired bias force. This prevents crushing of the case or overloading of the mechanism by shock loads or overtravel of the actuating system.

The component parts of the switch are relatively simple screw machine parts which are reproducible to close tolerances. No tapped holes or screws need be used in the switch, thereby further reducing manufacturing costs and providing a very simple assembly procedure.

The switch has a very high degree of reliability because, for example, the contacts are wiped free of foreign matter, such as particulate substances or ice, upon each closing. Reliability and switch life are increased, as compared with the conventional microswitch, by the reduction in friction, as previously noted, and further by the feature of the mechanism which prevents substantial deformation of critical components, thereby avoiding fatigue failures. Since the return biasing means are independent of the electrical circuitry, materials and structures which are essentially free of metal fatigue problems are easily obtainable.

In addition to the foregoing, the switch can be constructed in virtually any size and in a great many configurations to be adapted to multiple switching systems, heavy current switching systems, and for use in environments requiring custom design. Modification of the switch is accomplished simply by scaling up or down the size of the components, a feature which is not usually possible in the conventional

microswitch construction. For example, the inventive switch has been constructed with blades several inches long which pivot through an arc length of several inches.

The switch approximates a snap-action switch, and is easily adaptable to snap-action design, since once sufficient torque is available to overcome the initial at rest friction, then the blades pivot very rapidly and easily to the actuated position and, similarly, deactivate very rapidly, thereby reducing arcing during the make and break period.

As the foregoing discussion clearly indicates, a great many variations in the dimensions and construction of the fundamental mechanism and switch can be made based on the foregoing using the skill of the art without departing from the invention and the design principles set forth herein.

What is claimed is:

1. An electric switch comprising the combination of:
a pair of members pivotally secured proximate the ends thereof in relatively spaced relation;
means mounting said members individually intermediate the ends thereof for pivotal movement about pivot points respectively displaced asymmetrically from the respective centers of said members;
actuating means for reciprocally moving said mounting means transversely of the members thereby causing said members to pivot about said mounting means; and
electrical contact means positioned for being opened and closed by reversible pivotal movement of said members by said actuating means.
2. The switch of claim 1 wherein the actuating means includes bias means for resiliently constraining the mounting means toward each other and separator means for selectively moving the mounting means apart.
3. The switch of claim 2 wherein the members are pivotally connected proximate the ends thereof by a pair of end connectors, the members and the end connectors defining a quadrilateral which is variable in area and in width upon actuation and deactuation.
4. The switch of claim 3 wherein the end connectors and the members are so pivotally connected as to define a parallelogram of variable area.
5. The switch of claim 4 wherein the members are mounted to pivot respectively about pivot points displaced on opposite sides of the centers of the respective members.
6. The switch of claim 5 wherein the pivot points are displaced equal distances on opposite sides of the centers of the respective members.
7. The switch of claim 6 wherein the separator means displaces the pivot points by a distance ΔD , and the pivot points are displaced a distance ΔL , from the respective member centers, and the distances ΔD and ΔL being approximately equal.
8. The switch of claim 7 wherein the constraining means comprises at least one resilient generally annular member extending around the mounting means and being so disposed as to bias the mounting means toward each other and to be resiliently deformed upon actuation by said separator means.
9. The switch of claim 8 wherein the constraining means comprises two such annular members so disposed as to bias the top and bottom of the mounting means toward each other.
10. The switch of claim 9 wherein the electrical contact means comprises at least one contact set which comprises at least a pair of spring leaf contacts and at least one conductor, the conductor leaf being carried on a pivot member and the spring leaf contacts being mounted so as to be resiliently displaced and wiped by the conductor leaf upon actuation of said switch.
11. The switch of claim 9 wherein the electrical contact means comprises at least one spring leaf, and at least one conductor, and conductor leaf being carried on a pivot member and the spring leaf being mounted so as to be resiliently displaced and wiped by the conductor leaf upon actuation of said switch.
12. The invention of claim 11 wherein the mounting means comprises a pair of spaced frustoconical cam surfaces, the

separator means comprises cam operator having a cam-operating surface and means supporting said operator between said mounting means for reciprocal movement for moving said mounting means apart upon reciprocal movement of said operating surface upon said cam surfaces.

13. The invention of claim 11 wherein the separator means comprises an idler hub mounted between said mounting means and substantially in contact therewith and an operator rod mounted for being inserted between one of said mounting means and said idler hub, said mounting means being moved apart through contact with said operator rod and movement of said idler spindle.

14. The invention of claim 1 wherein said mounting means comprise hubs mounted proximate each other and said separator means comprises an operator rod mounted for movement between said hubs, said rod being of such dimension as to move said hubs apart.

15. The invention of claim 2 wherein the separator means comprises an idler hub mounted between said mounting means and substantially in contact therewith and an operator rod mounted for being inserted between one of said mounting means and said idler hub, said mounting means being moved apart through contact with said operator rod and movement of said idler spindle.

16. The invention of claim 2 wherein said mounting means comprise hubs mounted proximate each other and said separator means comprises an operator rod mounted for movement between said hubs, said rod being of such dimension as to move said hubs apart.

17. The invention of claim 2 wherein the mounting means comprises a pair of spaced frustoconical cam surfaces, the separator means comprises a cam operator having a cam-operating surface and means supporting said operator between said mounting means for reciprocal movement for moving said mounting means apart upon reciprocal movement of said operating surface upon said cam surface.

18. The switch of claim 17 wherein the members are pivotally connected proximate the ends thereof by a pair of end connectors, the members and end connectors defining a parallelogram which is variable in area and in width upon actuation and deactuation.

19. The switch of claim 18 wherein the members are mounted to pivot respectively about pivot points displaced a distance ΔL on opposite sides of the respective member centers.

20. The switch of claim 19 wherein the mounting means are displaced a distance ΔD upon actuation and wherein ΔD is approximately equal to ΔL .

21. The switch of claim 17 wherein the members are mounted to pivot respectively about pivot points displaced a distance ΔL on opposite sides of the respective member centers.

22. The switch of claim 21 wherein the mounting means are displaced a distance ΔD upon actuation and wherein ΔD is approximately equal to ΔL .

23. The switch of claim 2 wherein the electrical contact means comprises at least one contact at which comprises at least a pair of spring leaf contacts and at least one conductor, the conductor being carried on a pivot member and the spring leaf contacts being mounted so as to be resiliently displaced and wiped by the conductor upon actuation of said switch.

24. The switch of claim 2 wherein the members are mounted to pivot respectively about pivot points displaced a distance ΔL on opposite sides of the respective member centers.

25. The switch of claim 24 wherein the mounting means are displaced a distance ΔD upon actuation and wherein ΔD is approximately equal to ΔL .

26. An electrical switch comprising:

a switch housing;

a pair of blades;

end connectors pivotally interconnecting the respective ends of the blades to define a variable area parallelogram;

5

means mounting the blades in the housing for pivotal motion about respective pivot points and transverse motion of the pivot points of the respective blades;

means biasing the pivot points in a first direction; actuating means operable from without the housing for selectively reciprocally moving the pivot points relative to each other transversely of the blades, the coaction of the pivotal mounting means and pivotal interconnection of the blade ends causing said blades to pivot when the pivot points are so moved; and

contact means in the housing operable by the blades for opening and closing at least one circuit upon pivotal motion of said blades.

15

27. The switch of claim 26 wherein the mounting means comprises a pair of spaced hubs having cam surfaces thereon and the actuator comprises a cam operator supported for reciprocal movement between the hubs, said operator having a cam-operating surface adapted to coact with the cam surfaces on the hubs for moving said hubs apart in a second direction against the force exerted by the biasing means, the pivotal motion of said blades causing the cam operating surface and the cam surfaces to be in substantially rolling contact.

25

28. The switch of claim 27 wherein the blades are mounted to pivot respectively about pivot points displaced a distance ΔL on opposite sides of the respective blade centers.

30

29. The switch of claim 28 wherein the mounting means are displaced a distance ΔD upon actuation and wherein ΔD is approximately equal to ΔL .

35

30. The switch of claim 26 wherein the contact means comprises at least one contact set which comprises at least a pair of spring leaf contacts and at least one conductor, the conductor being carried on a blade and the spring leaf contacts being mounted so as to be resiliently displaced and wiped by the conductor leaf upon actuation of said switch.

40

31. The switch of claim 30 wherein the mounting means comprises a pair of spaced hubs having cam surfaces thereon and the actuator comprises a cam operator supported for reciprocal movement between the hubs, said operator having a cam-operating surface adapted to coact with the cam surfaces on the hubs for moving said hubs apart in a second direction against the force exerted by the biasing means, the pivotal motion of said blades causing the cam-operating surface and the cam surfaces to be in substantially rolling contact.

45

32. The switch of claim 31 wherein the blades are mounted to pivot respectively about pivot points displaced a distance ΔL on opposite sides of the respective blade centers.

50

33. The switch of claim 32 wherein the mounting means are displaced a distance ΔD upon actuation and wherein ΔD is approximately equal to ΔL .

55

34. As a mechanical movement for converting reciprocal motion to rotary motion, the combination comprising: a pair of elongate substantially rigid members;

end connectors pivotally interconnecting the respective ends of said members to define a variable-area quadrilateral;

means mounting the members for pivotal motion about respective pivot points and transverse motion of the pivot points of the respective members;

means biasing the pivot points in a first direction; actuating means for selectively reciprocally moving the pivot points relative to each other transversely of the members, coaction of the pivotal mounting means and pivotal interconnection of the member ends causing said members to pivot when the pivot points are so moved.

60

35. The movement of claim 34 wherein the mounting means comprises a pair of spaced hubs having cam surfaces thereon and the actuator comprises a cam operator supported for reciprocal movement between the hubs, said operator having a cam-operating surface adapted to coact with the cam surfaces on the hubs for moving said hubs apart in a second direction against the force exerted by the biasing means,

75

pivotal motion of said members causing the cam operating surface and the cam surfaces to be in substantially rolling contact.

36. The movement of claim 35 wherein the members are mounted to pivot respectively about pivot points displaced a 5 distance ΔL on opposite sides of the respective blade center.

37. The movement of claim 36 wherein the mounting means are displaced a distance ΔD upon actuation and wherein ΔD is approximately equal to ΔL .

38. A switch comprising the combination of:

a housing;

a pair of shafts supported in the housing;

a hub received loosely on each shaft for rotary and lateral movement;

at least one pivot lever supported by each hub;

a pair of connecting rods pivotally secured respectively to the ends of the pivot levers to form a quadrilateral;

resilient means biasing the hubs toward each other;

means operable from without the housing for displacing the

10

15

20

hubs laterally from each other for actuating the switch; and

means in the housing for making and/or breaking at least one electrical connection, including movable means associated with the pivot levers, constructed and disposed for being operated upon relative lateral movement of the hubs, such lateral movement resulting in pivotal movement of the pivot levers and generally longitudinal reciprocal movement of the connecting rods.

39. The switch of claim 38 wherein:

at least a pair of spaced pivot levers are supported on each hub;

the means for displacing the hubs comprises a cam movable along an axis perpendicular to the axes of the hubs; and the means for making and/or breaking electrical connection includes at least one set of electrical contacts and conductive means movable by the pivot levers for closing and opening an electrical circuit between said contacts.
